UNITED STATES PATENT OFFICE.

JOHN J. BOERICKE, OF MERION, PENNSYLVANIA.

APPARATUS FOR CARRYING ON METALLURGICAL OPERATIONS.

1,277,083.

Specification of Letters Patent. Patented Aug. 27, 1918.

Application filed July 20, 1914, Serial No. 851,884. Renewed June 29, 1918. Serial No. 242,693.

To all whom it may concern:

Be it known that I, JOHN J. BOERICKE, a citizen of the United States, residing at Merion, in the county of Montgomery and

5 State of Pennsylvania, have invented certain new and useful Improvements in Apparatus for Carrying on Metallurgical Operations, of which the following is a specification.

10 This invention has reference to apparatus for carrying out metallurgical operations, such, for example, as the reduction of metals from their ores and oxids. One of the primary objects of my invention is to obtain 15 through a series of successive operations, uniformity in the product to be reduced. Another object of the invention resides in the provision of an improved cabinet and fume condenser having the characteristics 20 specified, and in conjunction with the foregoing my invention also contemplates a control, from the exterior, of the material fed into the cabinet to be reduced.

The foregoing, together with such other 25 objects as may hereinafter appear or are incident to my invention I obtain by means of a construction which I have illustrated in preferred form in the accompanying drawing, wherein—

30 Figure 1 is a vertical section through my improved apparatus; and Fig. 2 is a section taken on the line II—II of Fig. 1.

While my invention can be utilized in carrying out a number of different reduction 35 processes, it is primarily adapted for use in connection with the reduction of metals by what is known as the aluminothermic process, and I will therefore describe it in connection with such process.

40 In the aluminothermic reduction of metals, the ore or compound which is to be reduced is mixed with aluminum or other reducing agent having a strong affinity for oxygen, and a reaction is instituted in a portion 45 of the mass, preferably by igniting a small portion of the mixture, the reaction spreading from this ignited portion throughout the mass. I prefer, however, to practice the aluminothermic reduction according to 50 the method defined in my co-pending application Serial No. 851,885 filed July 20, 1914, this method in brief consisting in placing a relatively small quantity of a mixture of 55 the compound and a reducing agent in a crucible, then in igniting such mixture and in feeding into the crucible, under control,

additional quantities of the mixture which is placed, for example, in a bin or hopper so as to have a gravity feed.

Referring to the drawings, I have indicated a crucible 7 which is carried on a truck 8 riding on the tracks 9. The track 9 passes through my improved cabinet device, which is in effect a closed chamber divided into two compartments, A and B, by a baffle wall 10. The tracks 9 pass through the chamber A which is provided with doors 11 and 12 respectively arranged on opposite sides of the chamber. Arranged adjacent to one side of the chamber A is a framework 70 13 which supports a bin 14 and a platform 15 on which an operator stands. A discharge spout 16 leads from the bin to the interior of the chamber A, passing through a slot or opening 17 formed in the side of 75 the chamber A. The discharge from the spout 16 is controlled by the operator by means of the valvular device 18 and handle 19. A condensing pipe 20 leads from the lower portion of the chamber B to the exterior of the cabinet, a draft being created 80 therein by means of an exhaust fan 21.

The operation is as follows: A crucible 7 containing a small quantity of a mixture of the compound to be reduced and aluminum, 85 is rolled into the chamber A, and the doors 11 and 12 are closed. The mixture in the crucible is then ignited by throwing a lighted taper through the opening 17 into the crucible, and after the reaction has started, 90 the operator—by manipulating the valvular device 18—feeds additional quantities of a mixture of the compound and aluminum into the crucible as fast as may be required, the reaction spreading from the ignited portion 95 to the material being added. When the crucible is sufficiently filled, the feed is cut off, and the reaction ceases, after which one of the doors is opened and the crucible rolled out and a new one brought in place. In 100 practice, I prepare enough material to fill four or five or sometimes even a greater number of crucibles. The length of the runs, however, is entirely dependent upon the quantity of the metal to be reduced. 105

It will be seen that in producing one of the rarer metals with given percentages of the various constituents, it is of the utmost importance to carry on the successive reductions under conditions as nearly alike as is 110 possible in order to obtain a uniformity of the resultant product and in order to elimi-

nate losses which would be incident to unacceptable variations in the product. I accomplish this by the use of the cabinet just described as it will be clear that the conditions are the same for each reduction. The importance of the manual control of the feed from the exterior will also be apparent inasmuch as the heat generated in the reduction is extremely intense. Manual control of the feed is advantageous and practically requisite because the reduction spreads from beneath upward from a relatively small initial quantity. If either too much or too little additional material is fed into the crucible, the results will not be satisfactory. The opening 17 provides a means whereby the operator can determine the condition of the reaction taking place, while at the same time he is adequately shielded from the heat. The fumes given off during the reduction are drawn into the chamber B over the baffle wall and thence into the condensing pipe 20, any excess amount thereof being exhausted into the atmosphere. By this combination of reducing cabinet and condenser, the operator is protected from the fumes and it is also possible to recover certain values of the material to be reduced which are contained in the fumes. This can be accomplished by a method such as defined in my co-pending application Serial No. 851,888 filed July 20, 1914.

I claim:

1. An apparatus for carrying out metallurgical operations comprising in combination a substantially inclosed reducing chamber having means for introducing a container, feeding means for supplying material from the exterior of the chamber to the container within said chamber, and means operable from the exterior of the chamber

for controlling the supply of material to the container.

2. An apparatus for carrying out metallurgical operations comprising in combination a substantially inclosed reducing cabinet having means for introducing a crucible, a hopper having a discharge spout leading into the cabinet, and a valvular control means for controlling the discharge operable from the exterior of the cabinet. 45

3. An apparatus for carrying out metallurgical operations comprising in combination a substantially inclosed chamber divided into a reducing compartment and 55 fume collecting compartment, a door in the reducing compartment for introducing a crucible, a hopper having a discharge spout extending into the said reducing compartment, and means operable from the exterior 60 to control the flow from the discharge spout.

4. An apparatus for carrying out metallurgical operations comprising in combination a substantially inclosed chamber, a baffle wall dividing the chamber into two connecting compartments, one a reducing compartment having means for introducing a crucible and the other a fume collecting compartment, a condensing pipe opening 65 from the collecting compartment, a feed pipe leading into the reducing compartment, and means operable from the exterior of the reducing compartment for controlling the feed through the feed pipe. 70

In testimony whereof I have hereunto 75 signed my name in the presence of the two subscribed witnesses.

JOHN J. BOERICKE.
